(57) **CLAIM**

The ornamental design for an audio/video appliance for
reproducing sounds or images, as shown and described.

DESCRIPTION

2.1 is a front view of an audio/video appliance for repro-
ducing sounds or images according to a first embodiment;

2.2 is a left side view thereof;

2.3 is a rear view thereof;

2.4 is a right side view thereof;

2.5 is a top view thereof;

2.6 is a bottom view thereof;

2.7 is a perspective view thereof;

3.1 is a front view of an audio/video appliance for repro-
ducing sounds or images according to a second embodiment
showing additional environmental features in broken lines;

3.2 is a left side view thereof;

3.3 is a rear view thereof;

3.4 is a right side view thereof;

3.5 is a top view thereof;

3.6 is a perspective view thereof; and

3.7 is a bottom view thereof.

The broken lines showing portions of the article in the
second embodiment form no part of the claimed design.

1 Claim, 14 Drawing Sheets
